Atty.*

UNITED STATES PATENT OFFICE.

EDWIN F. CALLENDER, OF GALESBURG, ILLINOIS, ASSIGNOR OF ONE-HALF TO L. BELLE CALLENDER, OF GALESBURG, ILLINOIS.

PRIMARY BATTERY.

1,215,774.

Specification of Letters Patent. Patented Feb. 13, 1917.

Application filed May 29, 1916. Serial No. 100,546.

To all whom it may concern:

Be it known that I, EDWIN F. CALLENDER, a citizen of the United States, and a resident of Galesburg, in the county of Knox and 5 State of Illinois, have invented a new and useful Primary Battery, of which the following is a specification.

My invention relates to portable batteries and especially to wet batteries, in which car- 10 bon, a depolarizer, and zinc form the ele- ments, and a solution of ammonium chlorid or other suitable salt is employed as the exciting fluid.

The object of the invention is to generally 15 improve the construction and increase the utility, durability and efficiency of batteries of this type, the improvements being directed more particularly toward the construction of the receptacle, toward the construction 20 and application of the container-cover, and toward several subsidiary improvements presently fully described.

The invention consists, substantially, in the improvements hereinafter described. 25 In the accompanying drawing, which illustrates a preferred embodiment of my invention:

Figure 1 is a vertical central section, partly in elevation and partly broken away, 30 showing the completed cell; and

Fig. 2, a perspective of the zinc element.

The jar or casing-shell 2 of my improve- 35 ment is preferably formed of tin, or of sheet-iron plated with tin whereby an eco- nomical basic structure is had. The casing- shell is entirely covered with asphalt 3, (preferably by dipping it therein while the latter is hot,) the nature of which is very adhesive, or "sticky" when not quite cold.

40 While the asphalt on the shell is yet warm I apply a cover or carton 4 of cardboard, pasteboard or the like which is either satured or coated with paraffin or a similar substance whereby to make it waterproof, 45 the heat and the nature of the asphalt caus- ing the cover to adhere firmly and closely thereto on both the sides and bottom. Inasmuch as the folding operation causes por- tions of the paper on the bottom to admit 50 moisture, I then apply a socket or cup 5 of paper or other suitable material, preferably waterproofed, and then dip the cup and the lower part of the cover into paraffin 6 or other similar waterproof material,

whereby to effectually exclude moisture 55 from the entire lower portion of the thus-far completed receptacle.

The asphalt on the interior of the can or casing shell is not, for two reasons, suitable as a lining. First, it is relatively soft, and 60 would easily be removed in spots by forcing the zinc element (presently described) thereto; and secondly, its surface is sticky or adhesive. In order, therefore, to overcome these objectionable features I fill 65 the cavity with hot pitch 7, which is then poured out and that left (and constituting the lining) allowed to harden. The surface presented by it will be extremely hard, 70 smooth and glassy, not liable to be injured by placements or removals of the zinc element, and allowing these with the greatest freedom.

The receptacle above described is of great 75 utility. The shell 2 is of an inexpensive ma- terial. The asphalt 3 coats every part thereof with a flexible, waterproof insulation and is easily and readily applied. The cover 4 adheres firmly and closely to the asphalt and will not readily be removed or 80 damaged by tearing therefrom or becoming loosened therefrom by moisture or other- wise, and it provides an additional measure of safety in that it is waterproof. The cup 85 or socket 5 and the paraffin 6 not only effec- tively exclude moisture from the lower parts of the receptacle, and especially the overlapped portions of the cover 4, but also provide a smooth bottom on which the article securely rests; while the hardened 90 pitch lining 7 is of great utility in affording a smooth, glossy, frictionless surface for the passage of the zinc element, in protecting the asphalt between it and the shell 2, and in adding a supplemental insulation against 95 electrolytic action between the elements 2 and 8.

The battery may be subjected to rough 100 handling without danger of injury thereto. Each of the parts of the receptacle stiffens, 100 protects and reinforces the others, and the fact that the yielding asphalt covers every portion of both the inside and outside of the can is an absolute protection against those inefficiencies as have heretofore been present 105 in batteries of this character.

8 designates the usual zinc element, to which is attached the negative wire 9. 10

denotes the carbon surrounded by any suitable depolarizing material 11 inclosed in a sack 20 held thereon by a cord 12. 13 designates a preferably chemically pure absorbent paper wrapper around the sack 20 and cord 12. These are common in the art.

When the parts 8-13 inclusive have been placed in the receptacle in the usual manner, a sufficient quantity of ammonium chlorid or 10 other suitable salt 19 is placed thereon to fill the receptacle to about the point indicated by 14, whereupon a vent-tube 15 is placed in position, resting on and preferably partly surrounded by the salt. Pitch or other suitable sealing material 16 is then used to completely fill the receptacle. The cap 17 may then, if desired, be removed from the tube 15, water poured thereinto to dissolve the sal ammoniac and charge the battery, and 20 the cap then replaced.

An air space, comprehended by the space which was occupied by the dry salt, is thus provided, and in this the gas may collect, without danger to the vent or other part of 25 the battery.

This construction is one in and by which spilling or evaporation are prevented and which is not only as clean as the ordinary dry battery, but which is effectively used on

vehicles which are subjected to shocks and 30 vibration.

While I have described and illustrated a wet battery it will be very clear to those skilled in the art that the receptacle hereinabove described is well adapted for a dry 35 battery, and therefore desire that no limitation of my claims be inferred because of such specific disclosures.

Having thus described my invention I claim as new the following, to-wit:

1. In a battery, a metallic casing-shell, asphalt covering its exterior, a waterproofed cover surrounding said asphalt, and asphalt covering the interior of the shell.

2. In a battery, a metallic casing-shell, asphalt covering its interior, and a pitch lining covering the asphalt.

3. In a battery, a metallic casing-shell, asphalt covering its interior and exterior, and a pitch lining for the interior asphalt.

4. In a battery, a metallic casing-shell, asphalt covering its interior and exterior, a pitch lining for the interior asphalt, and a paraffined cover for the exterior asphalt.

In testimony whereof I hereunto affix my 55 signature this 22nd day of May, 1916.

EDWIN F. CALLENDER.
